SHOE-BOTTOM-COATING MACHINE

Wilbur Le Roy MacKenzie, Beverly, Mass., assignor to United Shoe Machinery Corporation, Borough of Flemington, N. J., a corporation of New Jersey

Application October 20, 1937, Serial No. 170,078

39 Claims. (Cl. 12—80)

My invention relates to machines for applying an adhesive coating, it being particularly concerned with cementing the channels of shoe-soles.

When, in channel-cementing, the channel-bed is comparatively flat and does not vary greatly in width, as is commonly the case in Littleway work, less difficulty is encountered in the desired application of the adhesive to the bed and to the inner side of the channel-flap than, for example, when operating upon welt shoes. In shoes of the welt type, while the channel-bed at the forepart of the sole is usually flat, this is not true at the shank, and especially in women's shoes, where it is curved laterally and is wider than at the forepart. With such an applying device as an extruding nozzle, which has the flap-coating and bed-coating portions in fixed relation, proper delivery of the cement throughout the entire length of the channel of a welt shoe may be impossible because of the need for keeping the nozzle outlet almost in contact with the work. The difficulty is increased by abrupt changes in the form of the bed, as at the ball-line or juncture of the forepart and shank. The varying width and contour of the bed also gives trouble in obtaining a uniform application of cement. Further, in welt work, the channel-flap is often relatively thick, and in its turned-back position may be heavily wrinkled and lie close to the tread-surface of the sole, so it will be hard to lift to receive the action of the nozzle without marring such sole-surface. It is an object of this invention to advance the work for the channel-coating operation smoothly, without cramping, and in a position convenient for manipulation by the operator; to bring the flap free from irregularities to and hold it in its cement-receiving relation by means which will not injure the sole; and to accomplish all this by simple and strong elements which may readily be shifted into and out of their operating positions and be adjusted conveniently for work of different kinds.

In attaining this object, I have provided an oscillatory flap-engaging finger or member which is formed to lift the flap into effective co-operation with the nozzle, yielding with respect to the sole to avoid injury thereto; actuating and positioning connections for the finger, which allow it to continue its oscillation both while in active and inactive relation to the work; adjustments for the finger toward and from the nozzle, conveniently manipulated when the machine is in operation, and for said finger with respect to the tread-surface of the sole; and a feeding mem-

ber having a surface which advantageously engages the shoe-upper when this is at different distances from the root of the channel and which may be located to the best advantage for work of different dimensions and latched in an inactive position when desired.

The construction of the nozzle described herein is not claimed in this application because it forms the subject-matter of a divisional application Serial No. 214,262, filed June 17, 1938, in my name, for improvements in Nozzles for shoe-channel cementing machines.

In the accompanying drawings, a particular form of my improved apparatus is shown,

Fig. 1 being a front elevation thereof; 15

Fig. 2, a rear elevation;

Fig. 3, a broken, top plan view of the controlling connections;

Fig. 4, an enlarged side elevation, with parts broken away;

Fig. 5, a sectional detail of the driving connections for the feed-roll;

Fig. 6, a similar view of the latch for the feed-roll-arm;

Fig. 7, an angular view of the operating elements more closely associated with the work;

Fig. 8, a detail in broken elevation of the applying nozzle, seen from the side opposite the operator's position;

Fig. 9, a broken rear elevation of said nozzle; 30

Fig. 10, an angular view of the entire nozzle-structure, looking from the left in Fig. 1;

Fig. 11, an angular view of the flap-coating section of the nozzle, with the opposite plates of which it is made up separated from each other; 35

Fig. 12, a similar view of the bed-coating section and including a portion of the supporting member;

Fig. 13, a broken side elevation of the flap-engaging finger and its actuating connections, 40 and

Fig. 14, a detail in elevation, showing the nozzle in co-operation with the shank-portion of the sole.

A column 10 is shown supporting a head or frame 12 having spaced side-plates upon which are mounted the operating elements of the machine and including a forwardly extending arm-portion 14. Projecting from one side of the frame-arm is a horizontal bracket 16 (Fig. 7) 50 longitudinally slotted to receive the body 18 of a nozzle-structure by which cement is to be applied to the work. At 20, the nozzle-body overhangs and rests upon the bracket and is clamped thereto for ready removal by a double-armed 55

lever 22 fulcrumed upon the body and having threaded through its connecting yoke a screw 24. The point of this screw is turned against an inclined edge upon the overhang 20, and the rounded ends 28 of the arms are forced against the under side of the bracket to fix the nozzle in place thereon.

The cement is delivered to the work through two nozzle-sections 30 and 32 (Figs. 10, 11 and 12), which may be of metal or other rigid material and which respectively coat the inner face of the channel-flap and the bed of the channel. The flap-nozzle 30 is made up of two plates 34 and 36, the former resting against a vertical face 38 at the end of the body 18. The outer plate 36 is held against the inner, and said inner against the body, by screws 40. Extending downwardly along the body and opening through the face 38 is a passage 42 (Fig. 9) to which cement 20 is delivered by way of a pipe 44 rising from the top of the body. Flow through the passage 42 may be governed by a screw 48 threaded through the body 18, with its end extending into the passage. Through the plate 34 of the nozzle-section 30 is an opening 50, which registers with the passage 42 and with the upper extremity of a groove 52 in the plate 36. Opposite the lower portion of this groove is a recess 54 in the plate 34, and from the groove and recess lead grooves 30 56 registering with each other and forming a passage opening through the end of the nozzle-section to coat the root of the channel and a small fraction of the channel bed. Along this passage, the plate 36 is cut away to furnish a discharge-slot 58 (Fig. 10) of sufficient length to extend for the full width of a channel-flap applied to it. The point 57 of the section 30, entering the angle or root of the channel, furnishes a gage to position the work as the operator advances it. To this point, the walls 59 and 61 adjacent to the discharge-slot are inclined downwardly and outwardly. The surface 59 upon the plate 34 is arranged to receive contact of the channel-flap, but at 61 the plate 36 is depressed 45 to prevent the wall from wiping away the cement which has been deposited by the slot 58.

The bed-section 32 of the nozzle has an arm 60 provided with lugs 62, 62 lying at opposite sides of a projection from a bracket 64 attached 50 to the side of the body 18. Through the bracket-projection and the arm-lugs is a pivot-pin 66, its axis approximately intersecting the gaging end-portion 57 of the nozzle-section 30. Thus, the nozzle-section 32 may move toward and from 55 the channel-bed in a plane substantially parallel to section 30 about an axis coinciding with the point at which it is guided. Extending through the arm 60 is a passage 68 (Figs. 9 and 12) leading through an end-face 70. With it registers an opening 72 from a recess 74 in an inner plate 76 of the nozzle-section 32. A second plate 78 of this nozzle-section closes the outer side of the recess 74, both plates being secured to the arm by a screw 80. The inner side of the plate 65 78 is recessed at 82, the wall along the lower portion of this recess forming, with the lower edge of the plate 76, a slot 84, which will extend in a generally horizontal direction across the channel-bed being operated upon at the widest 70 point therein. To the root of the channel, a passage 86 delivers from the recess 74, 82 through the point of the nozzle-section 32. Cement is supplied to the recess by way of the passage 68 and a flexible tube or conduit 88 which joins said passage to the body-passage 42 (Fig. 9). Flow

through these passages 68 and 42 may be proportioned correctly by adjustment of the screw 48 which controls the passage 42 directly and forces the balance of the cement delivered by the pump into the passage 68. The edge of the nozzle-section in which is the slot 84 is drawn yieldably down by a tension-spring 90 joining a lateral projection from one of the lugs 62 to the nozzle-body. This allows the section to float over the bed of the channel, it rising and falling as the contour of said bed or the angle at which the operator presents the work varies. At all times, it remains in correct applying relation. The edges 91 of the nozzle-section 32 at each side of the slot 84 are shown as arcuate or curved 15 inwardly. This curve preferably lies between an arc which would approximate the maximum transverse curvature of the channel-bed, as at the shank of a shoe, and the chord of the arc, this corresponding to the comparatively flat bed 20 at the forepart. This mean nozzle-contour will give a proper delivery of cement to the bed about the entire channel. The length of the slot may be equal to the maximum width of the channel, as at the shank. Although a portion of the slot 25 may extend outside the narrower channel-bed at the forepart, cement will not be discharged here to drip from the nozzle, because the supply of cement may be made such that its adhesion to the sole of the shoe is necessary to complete its 30 flow from the nozzle. Outside the sole-edge, the cohesion of the cement and its adhesion to the nozzle retain it against discharge. To avoid interference with the cement which has been laid upon the channel bed by the slot 84, the edge 91 35 of the plate 76 is higher than the corresponding edge of the plate 78, as are also both the similarly located edges of the plates 34 and 36 of the nozzle-section 30 (Fig. 8).

Cement is introduced into the passage 42 40 through a flexible tube or conduit 92 extending from the pipe 44 and which may be joined to a source of cement under pressure, as a pump, indicated at 94 (Fig. 4). The pump may be actuated through spur-gearing 96 (Fig. 5) from a 45 main driving shaft 98 journaled transversely at the rear of the head and receiving power through a pulley 100. In the nozzle-pipe 44 is a valve 104 which may be opened and closed through a shaft 106 joined to its stem and under the control of a treadle-rod 107 in a manner later to be described. Included in these controlling connections is a shaft-section 108 having at its ends universal-joints, one of which is readily separable. Upon freeing the nozzle by releasing the 55 clamp-lever 22, this separable connection and the flexibility of the tube 92 permit the operator to immerse the nozzle in a tank 110 containing a solvent for the cement, so the nozzle may not become clogged when the machine is not in use. 60 From the tank, which is attached to one side of the head, projects a chamber 112 to receive the hose 88 of the nozzle-section 32 as the nozzle is placed in the tank, as shown in Fig. 2, with its lower extremity separated from the bottom wall. 65 A hinged cover 114 is provided for the tank and, inwardly from one edge, extends a slot 116 of sufficient width to receive the nozzle-body and the clamping lever 22, with the nozzle-overhang 20 resting upon the outer surface of the cover. 70 When thus positioned, the lever may be forced by the screw 24 into engagement with the inner cover-face to secure the nozzle as it was upon the head-bracket 16. With the nozzle mounted in this manner, the cover may be swung down 75

into place upon the tank with the delivery-openings of the nozzle immersed in the solvent. A spring-catch 118 separably secures the cover with the nozzle in place. The hose 92 is of such length that the operator may transfer the nozzle between its positions upon the head and in the tank without disconnection.

To aid the operator in advancing the work to receive its coating, there contacts with the upper of the shoe adjacent to the crease a roll 122 of some such yieldable material as rubber. It is secured to the upper extremity of an upwardly and outwardly inclined shaft 124 mounted to turn in an arm 126 pivoted for angular movement about the main shaft 98. The roll is shown as plano-convex in transverse section, the outer flat end lying close to the nozzle-sections. The opposite side is first curved at its edge 121 about a relatively short radius and then at 123 more gradually. The shaft 124 is journaled at its lower end in the arm and at its upper end in a sleeve 134. A sleeve 132 (Fig. 5) is rotatable in the arm 126 but is held against longitudinal movement. It is splined to the shaft 124 and is joined to the shaft 98 by spiral-gearing 136. The shaft 124 and the sleeve 134 are coupled to move together lengthwise by a flange 138 and a fixed collar 140 upon the former. Along the sleeve 134 extends a rack 142 with which meshes a pinion 144 arranged to rotate upon the arm and having turning with it a hand-lever 148. By actuation of the lever, the shaft may be shifted axially to vary the relation of the feed-roll 122 to the inner side of the nozzle-sections 30 and 32. This permits the roll to be positioned correctly with respect to the nozzle for soles of different thicknesses. In the chosen position of the lever, it may be secured by a draw-bolt having a thumb-nut 150. The operating relation of the roll to the work is adjustably determined by a stop-screw 151 threaded through the head 12 and with which the arm 126 contacts when it is lowered. Such downward movement is effected by a connection to the treadle-rod 107, as hereinafter described, this acting against the force of an expansion-spring 152 interposed between the head 12 and the arm 126 and urging the roll 122 toward a normally inactive position, shown in Fig. 4. When the machine is out of use, the roll may be secured in this inactive relation by a spring-pressed latch-pin 153 (Fig. 6) movable through the head 12. Into registration with this pin a recess 154 in the arm 126 will be brought as the arm reaches the position shown in Fig. 4. A projection 156 upon the pin cooperates with a slot 158 in the head and allows said pin, when rotated, to either assume its latching position in the recess 154 or to be maintained clear of the arm. This arrangement is useful, for example, when the operator finds it necessary to clear a clogged nozzle. At such time, a flow of cement may be produced through the nozzle by depressing the treadle-rod, and with the feed-roll latched up by the pin 153, the roll will be so disposed above the level of the nozzle outlet that it will not become soiled by dripping adhesive and cannot be moved by the treadle-rod.

To cause the nozzle-section 30 to act effectively upon the channel-flap, said flap is lifted into co-operation with the outer side of said section by a vibratory or oscillatory contact-finger 160. Pivoted at 162 upon the head 12 (Figs. 4 and 7) is a depending supporting arm 164 having rotatable at its divided lower end a

horizontal spindle 166. To this spindle, between the divided portions of the arm, is fixed a carrier-lever 168 (Fig. 13). To an outwardly extending portion of the carrier-lever a holder-lever 170 is fulcrumed, the angle of which upon the carrier-lever may be varied by a screw 172 threaded through the holder-lever and engaging a shoulder upon the carrier-lever. This engagement is normally maintained by a spring 174 interposed between the two levers. The holder-lever is grooved at 176 to receive the shank of the finger 160, a longitudinal adjustment of the finger in the groove being permitted by a slot-and-screw connection 178. The finger is inclined downwardly and inwardly and has a head 180 provided with an end-surface 182 of sufficient length transversely of the finger-shank to engage the channel-flap over its full width, the surface 182 being of substantial width considered longitudinally of the channel-flap. The lower edge 184 of the head 180 intersects the lower end of the flap-engaging surface in a smooth curve 184 and is arranged to move in proximity to or in contact with the sole being operated upon at the inner side of the flap. If said flap is turned back close to the tread-surface of the sole, the head of the finger, instead of riding over the flap, will with certainty raise and carry it to the nozzle-section 30, while the extended surface 182 may effectively force the flap against the section, beating and smoothing out any inequalities therein. The finger-adjustment provided by the screw 172 permits the operator to run the edge 184 close to the tread-surface of the sole, so the turned-back flap may be raised and yet the surface of the sole not marred by the oscillation of the finger-edge over it. If there is contact between the finger-edge 184 and the sole-surface, the spring 174 will yield and thus reduce the pressure upon the sole to an unobjectionable minimum.

The flap-lifting and -pressing movement of the finger 160 is preferably effected by oscillating the carrier-lever 168 through a connecting rod 198 pivoted to an upstanding arm of said lever. The opposite end of the rod is articulated to a generally vertical lever 192 fulcrumed upon the head and having at its lower extremity a roll 194 lying in a cam-track in a disk 196 fast upon the main shaft 98. The surface 182 of the finger is thereby rapidly pressed upon and withdrawn from the work, alternately holding it smoothly against the surface 59 of the nozzle over the delivery-slot 58 and freeing it to facilitate the feed. To position the finger with respect to the nozzle for operation upon channel-flaps of different thicknesses, a preliminary adjustment may be made at 178. To give a finer adjustment and one which may be used when the machine is in operation, the cam-lever 192 is fulcrumed upon an eccentric 197 fast upon a supporting spindle 198 rotatable in the head 12. Secured to the spindle is an arm 200 provided with a spring latch-pin 202, which may engage any one of a series of openings in a stationary segment 204. The turning of the spindle will shift the lever 192 and, through the rod 190, alter the angle of the carrier-lever 168 and, consequently, the space between the finger-head-surface 182 and the nozzle-surface 59. The extent of movement of the lever 192 will remain the same but the locus of its movement, and hence the movement of the finger 160, will be changed.

The feed-roll 122 is brought into active rela-

tion to the nozzle by depression of the treadle-rod 107, which also similarly acts upon the finger 160 and then opens the valve 104. Projecting outwardly from and arranged to turn about the spindle 103 is the horizontal arm of a bell-crank-lever 218, this, at its outer extremity, having an opening through which passes the treadle-rod 107. Fast upon the rod near its upper end is a collar 212, and between this and the bell-crank-lever is interposed a compression-spring 214. An upwardly extending arm of the bell-crank is joined by a link 216 to the arm 126 of the feed-rod. When the treadle-rod is drawn down, the movement is yieldably transmitted to the arm to swing the feed-rod toward the nozzle. Because of the pivoting of the arm about the driving shaft 93, this takes place without interference with the gearing 136. As to the corresponding movement of the finger 160 by the treadle-rod, a short, inwardly projecting portion of the supporting arm 164 (Fig. 13) has pivoted to it a link 220, which passes through an opening in a block 222 swiveled upon the upwardly extending arm of a bell-crank-lever 224 fulcrumed at 25 218 upon the head 12 (Figs. 3 and 4). Surrounding the rod and interposed between the block and nuts 228 upon the end of said rod is a compression-spring 231, which urges the block against a shoulder upon the rod. An inwardly extending arm of the lever 224 is connected to the treadle-rod. When the rod is drawn down, the lever 224, acting through the spring 231 and link 220, yieldably swings in the supporting arm 164 to bring the surface 182 of the finger into contact with the outer face of the channel-flap to lift it and force it toward or into engagement with the nozzle-section 30. The extent of movement of the finger toward the nozzle is limited by contact of a surface 232 (Fig. 13) upon the arm 164 with the machine-head. This shifting of the finger by movement of the arm 164 in no way interferes with the flap-smoothing oscillation imparted to said finger through the lever 158. Since, during the use of the machine, this oscillation continues uninterruptedly, a balance of the elements may be established, which will minimize vibration of the apparatus as a whole. Fulcrumed at 226 with the lever 224 is a generally horizontally extending lever 234 joined at its inner extremity by a link 236 to an arm 238 projecting from the shaft 106. The opposite end of the lever 234 is connected by a tension-spring 239 to the head, thus holding said lever against a stop 240 upon the head and the valve 104 normally closed. In the lever 234 is a slot 242, along which is movable an end of a pin 244 joining the treadle-rod 107 to the lever 224. When the treadle-rod is raised, and consequently the feed-rod 122 and the finger 160 are in their inactive positions and the valve 104 closed, the pin 244 engages the top of the slot. During the depression of the rod, the pin first travels idly through the slot while the feed-rod and finger are being brought into active cooperation with the nozzle. At this time, the pin contacts with the bottom of the slot, swinging the lever 234 and rotating the shaft 106 to open the valve. As a result of this sequential operation, the roll 122 is first brought lightly against the work and, upon continued depression of the rod, produces its feeding movement, with the channel-flap forced in proximity to or against the nozzle, and then, and only then, cement is delivered by the nozzle to the channel. Conversely, upon release of the treadle-

rod, the flow of cement is stopped, and then the work released by the feed-rod and finger.

In the use of this apparatus, the feed-rod 122 is so adjusted by manipulation of the lever 148 that the flat end-surface of said roll will lie close to the nozzle-sections 30, 32 but will clear the edge of the sole S of a shoe to be operated upon, whatever may be its extension or thickness. When in its active position, as shown in Fig. 7, the periphery of the roll will be in position to engage the shoe-upper U in proximity to the crease. The flap-pressing finger 160 may be so located upon its holder-lever 170 that the surface 182 of the finger-head will be sufficiently separated from the edge 59 of the nozzle-section 36 to give a space through which the finger may have its flap-pressing movement. The finger may be more exactly adjusted, even when the machine is in operation, by shifting the readily moved eccentric-arm 208. By altering the angle of the holder-lever 170 upon the carrier-lever 168 by turning the screw 172, the edge 184 of the finger-head 160 may be adjusted along the edge 59 of the nozzle-section 30 to cause this portion of the finger to lie sufficiently close to the tread-surface of the sole to insure lifting the channel-flap, without excessive pressure upon the sole. It should be observed that since the nozzle is stationary, adjustment of either the feed-rod or the finger is without effect upon the relation of the other of these elements to the nozzle, which need not be disturbed unless its adjustment is desired. With the machine in operation, the feed-rod is rotating and the finger is oscillating constantly, but normally both are raised by the rod 107, under the influence of the customary treadle-spring, to the positions illustrated in Fig. 4 of the drawings. The operator applies the channel of the sole, assembled with its upper, to the nozzle-section 30, the nozzle-point 57 lying at the root a of the channel (Figs. 7 and 8), and the sole being substantially horizontal, in which position it may best be seen and manipulated. The slot 84 in the nozzle-section 32 is drawn yieldably by the spring 86 into delivering relation with the channel-bed b. Upon lowering the treadle-rod, the connections to it swing down the arm 126 to bring the rounded edge 121 of the roll 122 into contact with the shoe-upper and carry in the supporting arm 164 to present the surface 182 of the finger 160 in pressing relation to the channel-flap c. The work thus being ready for advance, the rod-connections open the valve 104, so cement is delivered through the nozzle-slot 58 to the inner face of the channel-flap, through the slot 84 to the channel-bed and through the passages 56 and 58 to the root of the channel. The operator, aided by the rotation of the roll 122, feeds the work forward, the nozzle-point 57 serving as a gage throughout its travel. The finger-head 160, acting in its oscillation between the sole and the laid-back flap, raises the latter, yielding if the rounded edge 184 contacts with the tread-surface of the sole, and forces the flap up to the nozzle-section 30 at 59. This smooths out the wrinkles, which were produced when the channel was opened, and positions the flap to receive cement from the slot 58. As the channel is moved along the nozzle, the walls of the slot 84 in the section 32, under the influence of the spring 90, float over the channel-bed, accommodating themselves both to the changes of transverse contour and the angle of the channel resulting from the differing form of the bed, as between the forepart and shank, and from the position in 75

which the operator holds the work. The action will be better understood upon comparing the showing of Figs. 8 and 14 of the drawings, in which the nozzle appears, respectively, in co-operation with the channel at the forepart and at the shank of the shoe. The effect of the spring upon the section 32 also causes this to respond to changes in the contour of the bed which might be too abrupt for the operator to follow. When the forepart of the shoe, in its feed, is rocked on the gage-point 57 of the nozzle, the upper will move over the edge 121 (Fig. 4) of small curvature of the roll 122. At the shank, the increased rocking made necessary by the form of the shoe will transfer the area of contact to the roll-periphery 123 of greater curvature. In each instance, these lateral movements, through different angles and in the change from one to the other, will, because of the corresponding curvatures of the roll-periphery and their blending into each other, be effected smoothly, without interference with the advance of the work. Having coated the entire channel, the operator releases the treadle-rod 107, which is raised by its spring. The valve 104 is first closed, then the feed-roll and finger are returned to their elevated positions clear of the nozzle, and the completed work may be removed from the machine. If the operator wishes to clear the nozzle in event of clogging, the roll-arm 126 may be secured by the latching pin 153, where it will not be daubed by dripping cement. At the close of the working period, release of the clamping lever 22 allows the entire nozzle to be separated from the connection to the shaft-section 108 and from the head of the machine and be clamped upon the receptacle 110, with its cement-delivering portions immersed in the solvent.

Having described my invention, what I claim as new and desire to secure by Letters Patent of the United States is:

1. In a channel-cementing machine, a frame, a nozzle separably secured to the frame and comprising flap-coating and bed-coating sections movable relatively to each other, a flexible conduit connecting the nozzle to a source of cement, a flexible cement-conduit connecting the sections of the nozzle, and a receptacle mounted upon the frame and adapted to contain the nozzle, said receptacle having a laterally extending chamber to receive the conduit connecting the nozzle-sections.

2. In a channel-cementing machine, a frame, a nozzle separably secured to the frame and comprising flap-coating and bed-coating sections and having a projecting pipe, a flexible conduit connecting the pipe to a source of cement, a receptacle mounted upon the frame and adapted to contain the nozzle, and a cover for the receptacle having a slot in which the nozzle-pipe may be inserted with a portion of the nozzle resting upon the cover, the nozzle being provided with a clamping device for engagement with either the frame or the receptacle-cover.

3. In a channel-cementing machine, a frame, a nozzle separably secured to the frame and comprising a supply-pipe and flap-coating and bed-coating sections movable relatively to each other, a flexible conduit connecting the nozzle to a source of cement, a flexible cement-conduit connecting the sections of the nozzle, a receptacle mounted upon the frame and adapted to contain the nozzle, said receptacle having a laterally extending chamber to receive the conduit connecting the nozzle-sections, and a cover for the

receptacle having a slot in which the supply-pipe of the nozzle may be inserted with a portion of the nozzle resting upon the cover, the nozzle being provided with a clamping device for engagement with either the frame or the receptacle-cover.

4. In a machine for cementing the channels of shoe-soles, a nozzle arranged to act upon the channel-flap, a pivoted carrier, means to oscillate said carrier, and a movable finger yieldably mounted on said carrier provided with an end surface of substantial area for engagement with the channel-flap opposite the nozzle and a curved side surface arranged to travel close to the sole toward the channel-flap. 10

5. In a machine for cementing the channels of shoe-soles, a nozzle arranged to act upon the channel-flap, and a movable finger provided with a head having a surface for engagement with the channel-flap, the head projecting laterally from the finger and having a curved edge surface movable along the tread-surface of the sole and forming with the flap-engaging surface a smooth curve. 20

6. In a machine for cementing the channels of shoe-soles, a nozzle arranged to act upon the channel-flap, a movable finger provided with an end surface of substantial area for engagement with the channel-flap opposite the nozzle and a curved side arranged to travel close to the sole toward the channel-flap, carrier means pivoted substantially above the flap, and holder means pivoted on said carrier means at one side of the flap and permitting the finger to yield in contact with the surface of the sole. 35

7. In a machine for cementing the channels of shoe-soles, a nozzle arranged to act upon the channel-flap, a movable finger provided with a head having a surface for engagement with the channel-flap, the head projecting laterally from the finger and having a curved edge movable along the tread-surface of the sole, and a spring pressed against a side of said finger and urging the curved edge of the head toward the tread-surface of the sole. 40

8. In a machine for cementing the channels of shoe-soles, a nozzle arranged to act upon the channel-flap, a movable pressure-finger for engagement with the channel-flap opposite the nozzle and arranged to travel close to the sole toward the channel-flap, means including an oscillating lever for yieldably forcing the end surface of the finger against the channel-flap, means permitting the finger to yield in contact with the surface of the sole, means to oscillate the lever, and means to vary the locus of the oscillations. 50

9. In a machine for cementing the channels of shoe-soles, a nozzle arranged to act upon the channel-flap, a movable pressure-finger provided with a head having a surface at the side opposite the finger for engagement with the channel-flap, the head projecting laterally from the finger and having a curved edge movable along the tread-surface of the sole, a spring urging the curved edge of the head toward the tread-surface of the sole, and connections including a spring for yieldably forcing the head-surface against the channel-flap. 60

10. In a channel-cementing machine, a cement-applying device arranged to act upon the channel-flap, a movable support, a flap-engaging member oscillating upon the support toward and from the applying device, means for constantly thus oscillating the member during the operation of the machine, and a controlling member con- 70

- nnected to the support and movable by the operator to shift the flap-engaging member during its oscillation into and out of its active relation to the applying device.
11. In a channel-cementing machine, a frame, a nozzle carried thereby and arranged to deliver cement to the channel-flap, an arm pivoted upon the frame, a lever fulcrumed upon the arm, a flap-engaging member mounted upon the lever, connections to the lever for oscillating it, and a controlling member connected to the arm for actuation by the operator to change the position of the lever and member.
12. In a channel-cementing machine, a frame, a nozzle carried thereby and arranged to deliver cement to the channel-flap, a support movable upon the frame, a carrier movable upon the support, a holder yieldable upon the carrier, a flap-engaging member secured to the holder, means for moving the holder, and means arranged to move the support.
13. In a channel-cementing machine, a frame, a nozzle carried thereby and arranged to deliver cement to the channel-flap, a support movable upon the frame, a carrier-lever fulcrumed upon the support, a holder-lever yieldable upon the carrier-lever, a flap-engaging finger secured to the holder-lever, and means for oscillating the carrier-lever.
14. In a channel-cementing machine, a frame, a nozzle carried thereby and arranged to deliver cement to the channel-flap, a support movable upon the frame, a carrier-lever fulcrumed upon the support, a holder-lever fulcrumed upon the carrier-lever, a spring interposed between the levers, a flap-engaging finger secured to the holder-lever, means for oscillating the carrier-lever, and means arranged to move the support.
15. In a channel-cementing machine, a cement-applying device arranged to act upon the channel-flap, a flap-engaging member, a movable support for the member, means for moving the member upon the support for engagement with the channel-flap, means arranged to move the member upon the support to vary its normal relation to the applying device, and means arranged to move the support to render the member effective or ineffective.
16. In a channel-cementing machine, a frame, a nozzle carried thereby and arranged to deliver cement to the channel-flap, an arm movable upon the frame, a lever fulcrumed upon the arm, a flap-engaging member mounted upon the lever, connections to the lever for oscillating it, and means included in the connections for varying the normal position of the lever.
17. In a channel-cementing machine, a frame, a nozzle carried thereby and arranged to deliver cement to the channel-flap, an arm pivoted upon the frame, a lever fulcrumed upon the arm, a flap-pressing member mounted upon the lever, connections to the lever for oscillating it, means included in the connections for varying the normal position of the lever, and connections to the arm arranged to move it about its pivot.
18. In a channel-cementing machine, a nozzle arranged to deliver cement to the channel-flap, a flap-engaging finger movable toward and from the nozzle, a lever for moving the finger, and means arranged for manipulation by the operator to vary the fulcrum of the lever and change the relation of the finger to the nozzle.
19. In a channel-cementing machine, a nozzle arranged to deliver cement to the channel-flap, a flap-engaging finger movable toward and from the nozzle, a lever for moving the finger, an eccentric upon which the lever is fulcrumed, and means arranged to rotate the eccentric and fix it in different positions.
20. In a channel-cementing machine, a nozzle, a movable carrier, a holder movable upon the carrier, a channel-flap-engaging member carried by the holder and co-operating with the nozzle, means arranged to locate the carrier in different positions, and means arranged for manipulation by the operator to differently position the holder upon the carrier.
21. In a channel-cementing machine, a nozzle, a movable carrier, a holder movable upon the carrier, a channel-flap-engaging member carried by the holder and co-operating with the nozzle, means arranged to locate the carrier in different positions, means arranged for manipulation by the operator to differently position the holder upon the carrier, and means arranged to fix the engaging member in different positions upon the holder.
22. In a channel-cementing machine, a frame, a nozzle mounted thereon, a carrier-lever fulcrumed upon the frame, a holder-lever fulcrumed upon the carrier-lever, a channel-flap-engaging finger carried by the holder-lever, means arranged to vary the angular relation of the carrier-lever about its fulcrum, and means arranged to vary the angular relation of the holder-lever about its fulcrum.
23. In a channel-cementing machine, a frame, a nozzle mounted thereon, a carrier-lever fulcrumed upon the frame, a holder-lever fulcrumed upon the carrier-lever, a channel-flap-engaging finger carried by the holder-lever, means arranged to vary the angular relation of the carrier-lever about its fulcrum, means arranged to vary the angular relation of the holder-lever about its fulcrum, and means arranged to secure the finger in different positions upon the holder-lever.
24. In a channel-cementing machine, a frame, a nozzle mounted thereon, a carrier-lever fulcrumed upon the frame, a holder-lever fulcrumed upon the carrier-lever, a channel-flap-engaging finger carried by the holder-lever and co-operating with the nozzle, and a screw threaded into one of the levers and contacting with the other.
25. In a channel-cementing machine, a frame, a nozzle mounted thereon, a carrier-lever fulcrumed upon the frame, a holder-lever fulcrumed upon the carrier-lever, a channel-flap-engaging finger carried by the holder-lever and co-operating with the nozzle, a screw threaded into one of the levers and contacting with the other, and a spring normally holding the screw in contact with such other lever.
26. In a cementing machine for the channels of shoe-soles, a cement-applying device delivering cement to the channel, and a rotatable feeding member co-operating with the applying device and having a curved periphery for engagement with the shoe-upper, the curvature of the periphery adjacent to the applying device having a relatively small radius and that farther removed from the nozzle being of greater radius.
27. In a cementing machine for the channels of shoe-soles, a nozzle delivering cement to the channel and arranged to act thereon when the sole is in a substantially horizontal position, and a feed-roll rotatable about an axis inclined downwardly from the nozzle, the roll having a substantially plane end-surface in proximity to the nozzle and a curved periphery for engagement with the upper of the shoe.

28. In a cementing machine for the channels of shoe-soles, a nozzle delivering cement to the channel and arranged to act thereon when the sole is in a substantially horizontal position, and a feed-roll rotatable about an axis inclined downwardly from the nozzle, the roll having a curved periphery for engagement with the upper of the shoe, said periphery at its juncture with the end-surface being curved upon a relatively small radius and the remainder of the upper-engaging periphery being curved upon a greater radius.

29. In a cementing machine for the channels of shoe-soles, a nozzle delivering cement to the channel, a rotatable feeding member co-operating with the nozzle and having a curved periphery for engagement with the shoe-upper, and means arranged to vary the position of the roll along the axis of rotation toward and from the nozzle.

30. In a cementing machine for the channels of shoe-soles, a cement-applying device delivering cement to the channel, a rotatable shaft inclined downwardly from the applying device, a feed-roll carried by the shaft for contact with the upper of a shoe in co-operation with the applying device, and means arranged to move the shaft longitudinally.

31. In a cementing machine for the channels of shoe-soles, a nozzle delivering cement to the channel, a rotatable shaft extending from the nozzle, a feed-roll carried by the shaft for contact with the upper of a shoe in co-operation with the nozzle, a sleeve in which the shaft is rotatable, said sleeve being provided with rack-teeth, a pinion meshing with the rack-teeth, and means arranged to rotate the pinion.

32. In a cementing machine for the channels of shoe-soles, a nozzle delivering cement to the channel, a rotatable shaft extending from the nozzle, a feed-roll carried by the shaft for contact with the upper of a shoe in co-operation with the nozzle, a sleeve in which the shaft is rotatable, said sleeve being provided with rack-teeth, a pinion meshing with the rack-teeth, means arranged to rotate the pinion, and means by which the pinion may be secured against rotation.

33. In a channel-cementing machine, a cement-applying device acting upon the channel, a feed-roll co-operating with the applying device, a shaft by which the roll is carried, a driving shaft, gearing between the shafts, and an arm in which the roll-shaft is rotatable, said arm being arranged to turn about the driving shaft.

34. In a channel-cementing machine, a cement-applying device acting upon the channel, a feed-roll co-operating with the applying device, a shaft by which the roll is carried, a driving shaft, gearing between the shafts, an arm in which the roll-shaft is rotatable, said arm being arranged to turn about the driving shaft, an operator-controlled member by which the arm may

be moved upon the driving shaft to bring the roll into active relation to the applying device, and an adjustable stop by which the movement of the arm is limited.

35. In a channel-cementing machine, a cement-applying device acting upon the channel, a feed-roll co-operating with the applying device, a shaft by which the roll is carried, a driving shaft, gearing between the shafts, an arm in which the roll-shaft is rotatable, said arm being arranged to turn about the driving shaft, an operator-controlled member by which the arm may be moved upon the driving shaft to bring the roll into active relation to the applying device, an adjustable stop by which the extent of movement of the arm is limited, and a spring acting to urge the arm away from the stop.

36. In a machine for cementing the channels of shoe-soles, a nozzle for co-operation with the channel, a feed-roll arranged to engage the shoe-upper adjacent to the nozzle, a shaft by which the roll is carried, a pivoted arm in which the shaft is journaled and arranged to hold the roll below the nozzle in its active position, and means arranged to secure the arm with the roll above the level of the nozzle outlet in an inactive position.

37. In a machine for cementing the channels of shoe-soles, a frame, a nozzle secured to the frame for co-operation with the channel, a feed-roll arranged to engage the shoe-upper adjacent to the nozzle, a shaft upon which the roll is carried, an arm pivoted upon the frame and in which the shaft is journaled, said arm having an opening, and a spring-actuated pin movable upon the frame for engagement with the arm-opening.

38. In a channel-cementing machine, a frame, a cement-applying device fixed against movement on the frame for co-operation with the channel, a feeding member and a flap-engaging member situated at opposite sides of the applying device, means arranged to vary the position of the feeding member with respect to the applying member, and means arranged to vary the position of the flap-engaging member with respect to the applying device.

39. In a channel-cementing machine, a frame, a nozzle fixed against movement on the frame for co-operation with the channel, a feeding member and a flap-engaging member situated at opposite sides of the nozzle, means arranged to vary the position of the feeding member with respect to the nozzle, means arranged to vary the position of the flap-engaging member with respect to the nozzle, and means acting upon both members to move them into and out of active relation to the nozzle.
